BEVERAGE COOLING APPARATUS

Edward Freund, Long Beach, N. Y.

Application December 11, 1935, Serial No. 53,851

12 Claims. (Cl. 62—148)

My invention relates to beverage cooling apparatus and more particularly to coolers employed in connection with dispensing apparatus. In the systems now generally in use the beverage is conveyed through pipe lines extending from the container to a dispensing bar where block-tin tubing is arranged in coils in a cooler box or refrigerating chamber, the most common method of cooling being to fill the chamber with cracked ice. This tubing usually of three-eighths inch bore is arranged in a flat coil laid upon the bottom of the cooler box and the cracked ice is packed upon the coil. These coils usually consist of about fifty feet of tubing and the quantity of beverage contained in each coil under icing is approximately equal to thirty-six fluid ounces, or the contents of approximately five tumblers of the customary size in use at dispensing bars. This method therefore provides a very limited quantity of beverage under refrigeration, and when service is rapid, the temperature of the beverage soon rises above the desired degree, resulting in constant variations in temperature and requiring frequent re-icing and even with frequent re-icing the temperature of the beverage still varies rapidly owing to the limited quantity in the coils under ice. To overcome this objection additional cooling is provided in refrigerators where the containers are stored, but this provision does not entirely overcome the temperature variations because of the distance the pipe line extends from the container to the coils in the cooling box at the dispensing bar. In either case refrigeration is costly because of the frequent attention required and the amount of ice consumed.

In other dispensing systems one or more tanks are employed through which the beverage is caused to flow from the supply container or barrel to the dispensing faucet. These tanks are placed in cooling chambers to reduce the temperature of the beverage, but owing to the large volume in such tanks the cooling is relatively slow and the temperature varies with the rate of withdrawal. Furthermore in such tanks a considerable air space remains due to air compression as the tank fills with beverage, and when this pressure exceeds a predetermined degree due to the pressure from the supply container a vent valve automatically opens allowing air to escape which carries with it the gas which escapes from the beverage causing the beverage to lose its sparkle and run "flat".

It is also customary in beverage dispensing systems to employ air or gas pressure to force the liquid from the supply container to the dispensing

bar, and this pressure, in addition to the natural foaming of the beverage, causes undue foaming of the beverage as it discharges from the dispensing faucet resulting in considerable waste of beverage and loss of time in arriving at the desired fill for a tumbler.

One object of my invention is to provide a refrigerator for dispensing bars arranged in two sections, in one of which storage space is provided for cooling bottled beverages, etc., and the other section for cooling draft beverages. Another object is to provide a cooler for draft beverages whereby a more uniform, rapid and efficient cooling of the beverage is obtained. A further object is to reduce the foaming of the draft beverage when drawn from the dispensing faucet.

In carrying my invention into effect I provide a refrigerator having several compartments, one for the draft beverage cooler and others for storage of bottled beverages, and an ice chest having perforated walls centrally located relative to the storage compartments and extending the entire height and depth of said compartments. The ice chest will be filled with cracked ice which will always move toward the bottom as it melts, permitting refilling without disturbing the contents, and whereby the surrounding air will be uniformly chilled. In the refrigerating chamber for cooling the draft beverage I provide a cooler having one or more sections or chambers in the form of relatively long and wide, but very shallow flat tubes through which the beverage flows in a thin wide stream. These tube sections are disposed in the refrigerating box in such manner as to present a relatively large surface area to the cooling medium. These cooling sections will provide a much larger fluid capacity than the ordinary coil of tubing, will cool the beverage much more rapidly and uniformly and therefore consume much less ice, and owing to the shape will greatly reduce the foaming of the beverage when drawn from the dispensing faucet.

The cooling sections or chambers are preferably made of light gauge tinned sheet copper in the form of a shallow flat tube, the length being approximately three times the width, or more, and the depth three-eighths of an inch, or the same as the bore of the usual block-tin tubing ordinarily employed for cooling coils. These chambers are arranged in the cooling box to stand on the narrow edge with the inlet and outlet connections at opposite ends at the lower edge. The length of these chambers and their height will vary according to the cooling effect desired, but if for instance, the length were sixteen inches, the

height five inches, and the depth three-eighths of an inch, inside measurement, the capacity of the chamber would be thirty cubic inches, or sixteen and two-thirds fluid ounces, equivalent to the 5 capacity of twenty-three feet of the usual three-eighths tubing. In the preferred arrangement I employ these sections connected in series of two or more thus multiplying the beverage capacity in the cooler, and when for instance, three sections 10 are connected in series, a capacity equal to sixty-nine feet of tubing is obtained, or fifty fluid ounces of beverage, and still provide as much space for ice and much more effective cooling than would be possible with that length of tubing. 15 Thus my improved arrangement as compared to the usual fifty feet of coiled tubing results in an increase of approximately forty per cent in beverage capacity in the cooler and a reduction of approximately eighty per cent in the weight of 20 material employed.

I have found in practice that by the use of the long, narrow and relatively high, cooling sections the cooling effect is not only more rapid and uniform, but by arranging the inlet and outlet connections at the lower corners of the sections, the 25 foaming effect when drawing beverage at the dispensing faucet is greatly reduced. This I believe is due to the form and dimensions of the cooler section, that is, the relatively small lateral diameter, larger vertical diameter and long length of the chamber, and the natural tendency of the foam to rise while the flow of fluid is more rapid along the lower part of the chamber, that is, the direct line from inlet to outlet, and causing the foam to 30 accumulate in the upper part of the chamber. I further find that when two or more of these chambers are connected in series the foaming effect is successively reduced in each section. Furthermore, when a fresh container of beverage 35 is connected to the system it is usual to open the dispensing faucet to start the flow of beverage and with my cooling sections connected in the line all air will be driven out of the system, and thereafter practically no air will be present in 40 the cooling sections which will therefore fill completely with beverage and prevent any tendency of the beverage gases escaping from the liquid and thereby retaining the natural sparkle and avoiding "flatness" when drawn from the dispensing 45 faucet.

My invention is illustrated in the accompanying drawing in which, Figure 1 is a front perspective view of a dispensing bar or cabinet with the front and side of the casing partly broken away to show 55 the cooling sections; Figure 2 an enlarged cross-section of the cooling sections; and Figures 3 and 4 schematic views illustrating modified arrangements of the cooling sections.

Referring to the drawing, and more particularly to Figure 1, my improved refrigerator cabinet 1 is shown having doors 2, a drain shelf 3 formed in one or more sections of perforated sheet metal under which is a drain pan having a drain pipe 4 (not shown) connected to the main drain pipe 5. The lower section of cabinet 1 is divided into two storage compartments 6 and 7 having removable shelves 8 spaced from the walls of the compartments as shown at 9 to permit circulation of air. Between these two compartments is an ice chest having perforated sheet metal walls 10 on four sides, the front and rear walls of this chest being set in to provide spaces 11 to permit air circulation. The water from the melting ice drains into 75 pan 12 and through outlet 13 into drain pipe 4.

The ice chest 9 extends the entire height of compartments 6 and 7 and as shown also extends the entire depth, although this latter dimension might be less to allow for storage space on all four sides of the ice chest. I find that with this arrangement the cooling effect is more rapid and uniform and the ice consumption is greatly reduced. Furthermore, an ice chest arranged in the manner indicated for the use of cracked ice may be recharged more readily; the ice packs 10 more closely without voids; and recharging requires no removal of small lumps.

The upper part of the cabinet 1 is arranged into a separate refrigerating chamber 14 in which is placed the cooling sections 15 for draft beverages 15 to be dispensed from faucet 16. Only one draft beverage line is shown with a single dispensing faucet, but it will be understood that any number of beverage lines with cooler sections 15 and faucets 16 may be employed, in which case the 20 entire refrigerator will be longer, or only chamber 14 may be longer, and the beverage cooling units 15 may be disposed in groups of two or three sections, each group connected in series and placed in the chamber 14 as indicated schematically in 25 Figures 3 and 4. Chamber 14 is a metal lined box having a drain pipe 17 with overflow hole 18 to maintain the water from melted ice at the level of said hole. Above the chamber 14 is the usual 30 perforated drain plate 19 which covers a drain pan set into the top of chamber 14 and having a drain tube 20 entering drain pipe 17.

In the drawing I have illustrated in Figures 1, 2, and 3, three cooling sections 15a, 15b and 15c connected in series. These cooler sections are 35 preferably made of light gauge tinned sheet copper of any desired length and height, and quite narrow, the latter dimension being preferably the same as the diameter of the block-tin tubing connected to the supply line, usually three-eighths of an inch. These sections are positioned and suitably spaced parallel to each other and rest on their bottom edges in the refrigerating chamber 14. In the preferred form these sections have their end walls 21 slanting or curved downward as shown in Figure 1 and terminate in or are provided with nipples to which couplings 22 are secured. To the first or inlet section 15a is connected a supply tube 23. This tube will be of the usual three-eighths block-tin tubing and enters chamber 14 from or near the top and is coupled to the inlet end of section 15a by coupling 24 as shown in Figure 1. The supply tube 23 is connected outside the chamber 14 to the usual supply pipe leading from the beverage container stored at a convenient point or in a storage refrigerator, but since the supply system forms no part of the present invention same is not illustrated. The outlet from cooler section 15a is a block-tin tube 25 of three-eighths bore and is coupled to the inlet end of section 15b. The outlet tube 25 from section 15b is coupled to the inlet end of section 15c and the outlet end of section 15c is coupled to a block-tin tube 26 of quarter-inch bore which in turn is coupled to the dispensing faucet 16.

The outlet tube 26 leading to the dispensing faucet is of smaller bore than the outlet from the cooler section, but the bore of the faucet is of 70 larger diameter. The object of this arrangement is to reduce the pressure of the beverage as it flows from the cooler sections and reduce the velocity of flow to the faucet, and whereby the beverage is caused to issue from the faucet in a 75

5 relatively slow flowing solid stream instead of a rapid flowing jet or squirt as would be the case if the bore of the faucet and the tubing leading thereto were of the same bore or the tubing of larger bore than the faucet. I find that this arrangement when used for beverages having a natural gas content prevents frothing of the beverage as distinguished from the natural foaming due to the gas content, and consequently a tumbler 10 may be filled with the desired volume without having to remove or wait for the froth to subside. The tube 24 may be quite short but I prefer to use a length of about eight or ten feet extending between the outlet end of the last cooler 15 section 19 and the dispensing faucet 14, and in practice I arrange this tube in a coil either underneath the cooler sections 19 as shown in Figure 2, or coiled around the ends of the sections as illustrated in Figure 3.

20 For a dispensing bar having a number of dispensing faucets 14, the refrigerating chamber 13, as above stated, will be longer as customary, and the cooler sections 19 will be arranged end to end. That is, if for instance, two faucets 14 are provided, there will be two sets of cooler sections 19^a, 19^b and 19^c arranged in longitudinal alignment, and each set arranged as in Figure 1. When more than two faucets are employed, for instance three, a third set of sections may be added in the same 30 manner and the box 13 made correspondingly longer, or the individual sections 19 may be longer and arranged in tandem as illustrated in Figure 4. This latter arrangement is preferred for dispensing bars having a larger number of faucets 35 since the sections are very narrow and six lines of cooler sections may readily be placed in the refrigerating chamber 13 of the customary width and length. In a dispensing bar employing six faucets connected to the ordinary block-tin tube coolers, three hundred feet of tubing would be required weighing with connections over one-hundred and fifty pounds. This plus the weight 40 of the usual amount of ice required necessitates a refrigerator box construction capable of sustaining a weight of upwards of three-hundred pounds. It will readily be seen, therefore, that with my improved cooler sections of light gauge copper with small amount of tubing required for connections this weight will be greatly reduced 45 and that consequently the refrigerator box construction may be accordingly modified and greatly reducing liability of damage and need for repairs.

I have found in practice that by the use of cooler sections as illustrated, the cooling effect is 55 much more rapid than would be possible with the customary block-tin tubing of equal fluid capacity, and that by reason of the cooler sections being immersed in iced water the cooling is more uniform and requires much less icing.

60 What I claim is:

1. In a beverage dispenser, the combination of a cooling chamber and beverage conveyer within said chamber, said conveyer comprising a supply tube entering said chamber, a discharge tube for connection to a dispensing faucet, and a flat-sided tubular section of greater length than height and having downwardly tapering ends connected between said tubes.

2. In a beverage dispenser, the combination of 70 a cooling chamber and beverage conveyer within said chamber, said conveyer comprising a supply tube entering said chamber, a discharge tube for connection to a dispensing faucet, and two or more flat-sided tubular sections of greater length 75 than height having downwardly tapering ends

connected in series between said tubes.

3. In a beverage dispenser, the combination of a cooling chamber, a dispensing faucet mounted thereon, and a beverage conveyer within said chamber, said conveyer comprising a supply tube 5 entering said chamber, a discharge tube connected to said faucet and having a bore of smaller diameter than the outlet orifice of said faucet and of smaller bore than the supply tube, and a flat-sided tubular section of greater length than width 10 and relatively small cross-section connected between said supply and discharge tubes.

4. In a beverage dispenser, the combination of a cooling chamber, a dispensing faucet mounted thereon, and a beverage conveyer within said chamber, said conveyer comprising a supply tube 15 entering said chamber, a discharge tube connected to said faucet and having a bore of smaller diameter than the outlet orifice of said faucet and of smaller bore than the supply tube, and a 20 flat-sided tubular section of greater length than width and relatively small cross-section arranged on edge and having downwardly tapering ends connected between said supply and discharge tubes. 25

5. In a beverage dispenser, the combination of a cooling chamber, a dispensing faucet mounted thereon, and a beverage conveyer within said chamber, said conveyer comprising a supply tube entering said chamber, a discharge tube connected to said faucet and having a bore of smaller diameter than the outlet orifice of said faucet and of smaller bore than the supply tube, and two or 30 more flat-sided tubular sections of greater length than width and relatively small cross-section 35 connected in series between said supply and discharge tubes.

6. In a beverage dispenser, the combination of a cooling chamber, a dispensing faucet mounted thereon, and a beverage conveyer within said chamber, said conveyer comprising a supply tube entering said chamber, a discharge tube connected to said faucet and having a bore of smaller diameter than the outlet orifice of said faucet and of smaller bore than the supply tube, and two or 40 more flat-sided tubular sections of greater length than width and relatively small cross-section 45 arranged on edge and having downwardly tapering ends connected in series between said supply and discharge tubes. 50

7. A cooling apparatus for liquids having in combination a cooling chamber, inlet and outlet pipes for the liquid to be cooled, and a liquid chamber connected between said pipes having approximately parallel vertical walls of greater 55 length than height and spaced approximately equal to the bore of the inlet pipe whereby the liquid within said chamber will be presented for cooling in a long, wide and thin stream of relatively small volume and large area. 60

8. A cooling apparatus as defined in claim 7 having the inlet and outlet ports of the liquid chamber at the bottom edge thereof at opposite ends and in longitudinal alignment to provide straight line flow of liquid along the bottom of 65 the chamber.

9. A cooling apparatus for liquids having in combination a cooling chamber, inlet and outlet pipes for the liquid to be cooled, and a plurality of separate liquid chambers having approximately 70 parallel vertical walls of greater length than height and spaced internally approximately equal to the bore of the inlet pipe and coupled in series between said pipes whereby the liquid to be cooled will flow successively through said chambers and 75

be presented for cooling in successive long, wide and thin streams of relatively small volume and large area.

5 10. A cooling apparatus as defined in claim 9 having the inlet and outlet ports of the liquid chambers at the bottom edges thereof at opposite ends and in longitudinal alignment to provide straight line flow of liquid in each chamber along the bottom thereof.

10 11. In a dispenser for gas containing beverages, a conveyer comprising a supply pipe, a discharge pipe and dispensing faucet connected thereto, and a liquid chamber connected between said pipes having approximately parallel vertical walls of greater length than height and spaced approximately equal to the bore of the supply pipe and having the inlet and outlet ports at the bottom edge thereof at opposite ends and in longitudinal alignment to provide straight line flow of liquid 15 along the bottom of the chamber, and whereby

the foam due to the gas content will rise in said section and reduce the foaming at the discharge faucet when opened for discharge.

12. In a dispenser for gas containing beverages, a conveyer comprising a supply pipe, a discharge pipe and dispensing faucet connected thereto, and a plurality of separate liquid chambers having approximately parallel vertical walls of greater length than height and spaced internally approximately equal to the bore of the supply pipe 10 and coupled in series between said pipes and having the inlet and outlet ports at the bottom edge thereof at opposite ends and in longitudinal alignment to provide straight line flow of liquid along the bottom of each chamber and whereby 15 the foam due to the gas content of the beverage will rise in each chamber and cause decreased foaming successively in each chamber and reduce the foaming at the discharge faucet when opened.

EDWARD FREUND. 20
